UNITED STATES PATENT OFFICE

2,006,870

MATERIAL HANDLING APPARATUS

Jacob J. Neuman, South Salem, N. Y.

Original application February 23, 1933, Serial No. 658,069. Divided and this application February 26, 1934, Serial No. 712,994

2 Claims. (Cl. 198—34)

This invention relates to material handling apparatus, more particularly to trolley hoists and a therewith associated conveyer mechanism constructed and arranged to automatically space the articles being conveyed. This application for patent is a division of my copending application for patent, filed February 23, 1933, Serial No. 658,069, which has matured into Patent No. 1,988,855, granted January 22, 1935.

10 My invention is illustrated in connection with a relatively simple apparatus whereby commodities, such as raw sugar, may be expeditiously handled at the dock or pier for the purpose of first weighing the same, and then transporting the weighed bags or packages to the conveyer mechanism so that the manual labor heretofore incident to the handling of such materials may be reduced to a minimum.

20 In the illustrated application of my invention trolley hoists are mounted on a pier or dock, each hoist having means for raising and lowering a plurality of bags of sugar or other material, and the load of each hoist is first positioned upon the weighing scale, and after being weighed, is then transported to a position above the conveyer mechanism and the load discharged thereon.

25 My invention has for its object and purpose to provide means for transporting the bags of sugar or other material from the unloading station embodying high and low speed conveyers arranged in alignment, said low speed conveyer receiving the bags thereon in superimposed relation, and means interposed between said conveyers for effecting the separation of the bags and their single delivery in succession from the low speed to the high speed conveyer, from which the contents of the bags are adapted to be discharged into a receiving hopper or bin.

30 With the above and other objects in view, the invention consists in the improved material handling apparatus, and in the form, construction and relative arrangement of its several parts as will be hereinafter more fully described, illustrated in the accompanying drawing and subsequently incorporated in the subjoined claims.

40 In the drawing, wherein I have illustrated one simple and practical embodiment of my present improvements, and in which similar reference characters designate corresponding parts throughout the several views,—

45 Figure 1 is a plan view illustrating one installation of my present invention and showing the same arranged upon a pier or dock for handling the bags of material as they are unloaded from 50 the hold of the vessel; and

Fig. 2 is a sectional view taken substantially on the line 2—2 of Fig. 1.

5 Referring in detail to the drawing, wherein for the purpose of illustration I have shown one application and use of my present invention, a continuous monorail track 5, preferably though not necessarily, having a cross-sectional I-beam form is suitably supported upon the water front dock at which the cargoes of vessels are to be unloaded. A number of electrically controlled hoists 10 generally indicated at 6 are mounted in suspended relation from the continuous monorail 5 for longitudinal traveling movement.

15 At a suitable point upon the dock beneath one side of the monorail 5, the government and merchant scales generally indicated at S upon which the bags of sugar are to be weighed, are suitably positioned. At a proper point so as to stop the traveling hoist and its load above the scales S, a solenoid switch 40 is mounted at one side of the 20 monorail 5. A similar switch is also mounted at a suitable point in advance of the scales S and is actuated to switch releasing position by the solenoid indicated at 44. The circuits of these solenoids 40 and 44 may be closed by the 25 operation of a common push-button or other type of switch arranged at the office or house of the scale attendant.

30 There is also fixed to one side of the monorail 5, a shoe 45 which operates a normally open switch to close the lowering circuit of the hoist when the hoist arrives at the unloading position. A lever 47 at the top of monorail 5, opens a switch to break the circuit thus bringing the 35 trolley to a stop.

35 Arranged below one end of the rectangular track or monorail 5 is the end of a low-speed load-receiving endless conveyer 50 driven by the motor 51. This conveyer at or adjacent one of its ends has its upper stretch or run disposed in an obliquely inclined plane as at 53 by engaging the same around the vertically and laterally spaced sprocket 52. Arranged below and substantially in alignment with the obliquely inclined section 53 of the conveyer 50, is a guide 40 chute 54 which guides and directs the sugar bags upon the upper stretch or run of the high-speed conveyer 55 preferably arranged in longitudinal alignment with the conveyer 50 and driven by a separate motor 56. The sugar bags or the contents thereof may be delivered from conveyer 55 in any suitable manner into the receiving hopper or bin indicated at 57.

45 When the hoists arrive above the end of the conveyer 50, the load of sugar bags is lowered 50 55

upon the end of conveyer 50, where an operator is stationed to release said bags from the hoist. The sugar bags are received upon this conveyer 50 without regard to distribution thereof and 5 in superimposed relation. When the bags reach the inclined section 53 of conveyer 50, the upper bags fall downwardly thereon over the lower bags which are in direct contact with the conveyer and are guided by the chute section 54 to 10 the high speed conveyer 55. Therefore, owing to the relatively high speed of travel of the latter conveyer, the bags will be received upon the latter from conveyer 50 in a more or less separated relation. This is of course absolutely necessary 15 where the individual bags are opened to deliver the contents thereof into the bin or hopper 57.

From the foregoing description considered in connection with the accompanying drawing, it is believed that the construction, manner of 20 operation and several advantages of my invention as herein disclosed will be clearly and fully understood. It will be seen that I have provided a simple and reliably operating apparatus whereby such heavy bags of sugar or other material may 25 be expeditiously handled, weighed and transported to a predetermined destination. The several operations may be carried out with absolute safety, both to the apparatus and to the necessary attendants in charge thereof, and the manual 30 labor which has heretofore been incident to the handling of such materials to be reduced to a minimum.

In the foregoing description of the accompanying drawing, I have disclosed one embodiment 35 of the essential features of my present invention, which I believe to be entirely practical for the purpose in view. It is nevertheless to be understood that my invention is capable of embodiment in many different environments and may also 40 be incorporated in various other alternative structural forms, and I accordingly reserve the privilege of resorting to all such legitimate changes in the form, construction and relative arrangement of the several parts as may be fairly 45 embodied within the spirit and scope of the invention as claimed.

I claim:—

1. In a conveying and distributing apparatus 45 for superposed bags of sugar or the like, two unconnected and separately organized conveyers, 50 one comprising a bag-receiving conveyer and the other a bag-discharging conveyer, the former receiving the bags in superposed arrangement from a source of supply and being located in a plane 55 higher than the plane of the latter and having as a component part thereof a rear end conveying

portion inclined downwardly at a sharp angle from the main body of the conveyer and toward the surface of the discharging conveyer, means for operating the receiving conveyer at relatively low speed, means for simultaneously operating the discharging conveyer at relatively high speed, and downwardly inclined stationary means established between said rear end portion and the surface of the discharging conveyer, said means constituting a continuation of said rear end portion and being in surface alignment therewith for receiving bags therefrom and having an overall length sufficient to provide time in which all of the received bags will by reason of their descending force and weight assemble thereon in 15 direct contact therewith in single row order for discharge one behind the other from the stationary means on which they are so assembled, directly onto the surface of the discharging conveyer, said downwardly inclined rear end conveying portion being effective to give superimposed bags a definitely controlled downward momentum for casting them off balance and into proper place in the single line order.

2. In a conveying and distributing apparatus 25 for bags of sugar or the like, the combination of a high-speed conveyer and a separate low-speed conveyer, the latter disposed to convey in the direction of its length in a plane higher than the plane of the high-speed conveyer and having 30 as component parts thereof a horizontal portion and a rear end portion inclined downwardly at a sharp angle from the horizontal portion and toward the surface of the high-speed conveyer, a separate slideway device interposed downwardly 35 between said rear end portion and the surface of said high speed conveyer with its surface in alignment with the surface of said rear end portion and with its opposite ends in clearance relation to said respective parts, said low speed conveyer 40 having capacity to convey bags in superposed row arrangement and its rear end portion being effective through its sharp downwardly inclined operation to cause definite separation and dislodgment of the superimposed bags so as to enable them 45 to settle into proper alternating positions with the bags in the single row, and said slideway device having an overall course sufficient in extent to permit the settling bags to come in direct contact with said device so that all of the bags will 50 slide in single row arrangement upon the sliding surface of the said device prior to their successive discharge thereby upon the surface of the high-speed conveyer.

JACOB J. NEUMAN.
